UNITED STATES PATENT OFFICE

2,428,304

HOLLOW CENTRIFUGALLY MOLDED BEAM
 Paul Abeles, Vienna, Austria and Ernst Braun-
 bock, Dugaresa, near Karlovac, Yugoslavia

Application October 8, 1936, Serial No. 104,730
 In Austria October 28, 1935

Section 3, Public Law 690, August 8, 1946.
 Patent expires October 28, 1955

1 Claim. (Cl. 72—66)

1

In the past, attempts have been made to provide pre-fabricated hollow reinforced concrete beams for the construction of floors. These have the advantage that they do not require shuttering and enable the building operation to be speeded up. Moreover, they have great lateral stiffness and for this reason are particularly suitable for floors sufficiently rigid to exclude the possibility of oscillation. However, on the sides adapted to take up compression stresses these beams had to be made with a considerable wall thickness, whereby the weight of the beams was made relatively great. Furthermore, it is known to produce masts and conduit pipes of reinforced concrete by a centrifugal process, the longitudinal reinforcement being uniformly distributed over the whole of the annular cross sectional area.

The invention consists in the special construction of a hollow centrifugally molded beam of reinforced concrete for use in building construction especially in floors, said beam being substantially tubular in cross section, and including a main longitudinal reinforcement provided in the part of the tube required to endure tensile stress, and several longitudinal bars forming a secondary reinforcement arranged in the other parts of the tube; said beam also having a surrounding reinforcement interconnected with both said longitudinal reinforcement to form a rigid frame work of the beam, so that they act jointly.

Such a combination results in tubes of great carrying capacity while having comparatively thin walls and renders it generally unnecessary to increase the cross sectional area in the compression zone of the beam. The strength of centrifugally cast concrete being much greater than that of ordinary molded concrete, tensile stresses are set up in the surrounding reinforcement which relieve the longitudinal reinforcement to some extent. Beams constructed according to the invention are therefore lighter and much more economical, not only as compared to the known centrifugally cast concrete tubes, but also in comparison to any reinforced concrete beams. Owing to the increased load carrying capacity it is of advantage to employ the hollow reinforced concrete beams as joists or sills and summers and as floor beams. In the latter case the hollow beams may be laid as desired side by side contiguously or with spacing. The interspaces may be bridged over by reinforced concrete, concrete, light slabs or hollow bricks. Various embodiments of the invention are illustrated in the accompanying drawings showing in cross section parts of floors and beams of various forms.

2

Fig. 1 shows a floor consisting of a series of hollow beams 1 made according to the centrifugal casting process, between which floor filling bodies 2 are formed, made of any suitable material having a sufficient load carrying capacity for example, hollow bricks or stones of light concrete. The embodiment shows hollow beams with octagonal cross section, which are particularly easy to cast centrifugally. In Fig. 1, for example, two reinforcing members 3 are shown disposed in the lower zone, which must be marked as such so as to ensure that the beam is built into the wall or floor correctly. At other parts of the tubular beam weaker members 2^a are provided, to hold the surrounding reinforcement or rings in position. Since these are connected to the longitudinal reinforcing bars at individual points, a stiff reinforcing framework is formed, which increases the carrying capacity of the hollow beam in comparison to one formed by molding and compressing only. In this manner, the new beam is a combination of a tube and of usual beams of reinforced concrete. Hitherto, the reinforcement of the tubes was evenly distributed, while the usual beams are provided with longitudinal bars only in the zone of tensile stress with upwardly bent parts to endure the thrust, and with stirrups. According to the invention, the main longitudinal reinforcement is the same as in the usual beams, but a secondary longitudinal reinforcement is distributed over the other parts of the cross sectional area, and both reinforcements are interconnected by a surrounding reinforcement to form a rigid frame work so that they work jointly.

Instead of the bodies 2, which fill up the whole space between two adjacent carrier beams 1, concrete connecting arches may be constructed between the carrier beams with the aid of arched shuttering, which may be disposed at any desired level, since they do not take compression stresses. The flat lower surface may be made for example by a suspended trimming secured to wires which extend from the hollow beams.

In the embodiment according to Fig. 2 a reinforced concrete plate 4 is disposed between two adjacent hollow beams 1 flush with the lower surface thereof, whereby not only is a thorough concrete surface obtained as an underface, but erection without shuttering is made possible, since only ready made concrete parts are to be connected together. The slabs or plates 4 are held in place by wires 5, which are connected to the reinforcing wires 6 of the slabs. The ends 55 of the wires 6 which extend from the slabs are

bent to form eyes and the wires 5 are secured, for example, to the hollow beams 1. In the space above the slabs 4 a floor filling 7, for example, ashes, cinders or the like is disposed. If the space is filled with concrete, it is sufficient to attach the upper ends of the wires 5 temporarily to the beams 1, since after the concrete has hardened they become fixed therein.

As shown in Fig. 3, the slabs 4^a may also be secured in position by a rabbet joint, the tongue 8 being formed in this case on the beams 1^a and the groove 9 on the slabs, but this arrangement could of course be reversed. The tongue 8 may extend over the whole length of the beam, or it may be of short lengths distributed over the length of the beam. If a plane undersurface is not required, the slabs 4^a are disposed at a higher level, as shown in Fig. 4, in order to reduce the quantity of floor filling required. Another construction of this kind is shown in Fig. 5, wherein the slabs 4^{aa} rest on ledges 21 of the beams 1^b.

Fig. 6 shows an embodiment of the hollow beam, which forms a closed plane concrete underface if the beams are placed side by side. In this embodiment the width of the underface 10 is equal to the width of the beam 1^c. This construction is suitable for centrifugally cast hollow concrete beams of light cement (pumice cement). The smaller strength of the light concrete hitherto prohibited its use for carrying bodies. However, the strength is increased by the centrifugal process and thus the above objection is eliminated. It is of advantage that by the employment of light concrete beams placed side by side as floor carriers insulation is also assured.

According to Fig. 7 the lower zone of the beam 1^e is widened by the provision of two lateral extensions 11. In this case again a closed underface is obtained by placing the beams side by side. A saving of material is effected by providing a constriction 13 where the extensions 11^e join the walls of the hollow beam.

As shown in Fig. 8, slabs 4^f may also be employed in connection with hollow beams provided with extensions 11^f, so that the beams according to Fig. 7 may be spaced in the same manner as those according to Figs. 1 to 5. The slabs 4^f are provided in this case with flanges 16^f which rest on the extensions 11. In this case a continuous concrete surface is again provided as an underface and it is possible to carry out the construction without shuttering. The slabs 4 may also be replaced by carrying hollow bricks, in which case similar brick slabs are placed in position in the centrifugal mold prior to the charging of the latter with concrete, so that the bricks

adhere to the lower face of the beam and form a continuous under face when the beams are placed in position side by side.

Although the employment of the centrifugal casting process generally is not essential to form the tube with greater thickness of the upper zone, such reinforcement may be employed in some cases. Fig. 9 shows such a construction with reinforced upper zone 15.

If the beam is to be utilized as a window or door joist or as a sill, any one of the cross sectional forms described above may be employed. As summers beams of the cross section shown in Fig. 10 are particularly suitable. In this form the beam 1^g is formed with ledges 21^g similar to the ledges 21 of the beams shown in Fig. 5, such ledges acting as supports for beams or the like. By the provision of projecting iron parts and subsequent trimming it is possible to connect together summers, beams and slabs to form a monolithic whole.

It will be understood that in Figs. 2-10, the beams are reinforced in the manner described and shown in Fig. 1.

We claim:

A reinforced centrifugally molded concrete beam, said beam being substantially tubular in cross section, at least two longitudinally extending reinforcing members formed in said beam adjacent one surface only thereof, the part of the tubular wall opposite that part of the wall containing the main reinforcement being thicker than the other parts, a plurality of spaced and transversely arranged and substantially annular reinforcing members in said beam, said members being connected to said longitudinally extending reinforcing members whereby to form a stiff three-dimensional frame work for said beam.
